UNITED STATES PATENT OFFICE.

GRANVILLE ADAMS, OF HAMILTON, OHIO.

TIE-PLATE AND CLAMP.

1,396,805.

Specification of Letters Patent. Patented Nov. 15, 1921.

Application filed May 11, 1921. Serial No. 468,672.

To all whom it may concern:

Be it known that I, GRANVILLE ADAMS, a citizen of the United States, and a resident of Hamilton, in the county of Butler and 5 State of Ohio, have invented certain new and useful Improvements in Tie-Plates and Clamps, of which the following is a full, clear, and exact description, reference being had to the accompanying drawings, forming 10 part of this specification.

My invention relates to tie plates and clamps for railroad practice.

In the past, so far as I am advised, tie plates for use in laying rails have been 15 merely flat plates with the spikes therein engaging over the base of the rail to hold it down. In such construction the failure of spikes on the inside or outside of any tie plate will permit the rail to shift in the direction in which the spikes are gone. Also 20 in relaying rails there is always a chance of spreading until the rails are fully spiked down, thereby increasing considerably the time required to relay rails over a busy track, 25 since a good sized crew must busy itself with each rail to get the old one out and the new one in, between trains. This applies also to replacing of ties.

The object of my invention is to provide a 30 tie plate combined with a clamp which will hold a rail firmly to a tie so long as the tie plate is not free to shift and when used at joints between rails will hold the joints against spreading or the rails from shifting 35 lengthwise. Usually only one of such clamps is needed to prevent shifting of a rail, but in turn tables, scales, and the like, it is my object to prevent shifting in any direction of the rails by use of my plates with clamps on 40 both ends thereof.

These objects I accomplish by that certain construction and arrangement of parts to be hereinafter more specifically pointed out and claimed.

45 In the drawings,

Figure 1 is a perspective view of the tie plate and clamp assembled over a rail, which is merely dotted in.

Fig. 2 is a perspective view on a larger 50 scale of the clamp member for the left hand side of the tie plate.

The tie plate is made up of a base 1 on which the base 2 of a rail will rest. At the inside of this base (i. e. the inside of the track 55 when laid) are the usual holes 3, 3, for spikes 4 (dotted).

At a point where the outer side of the rail flange will rest is formed a shoulder 5 which acts as an abutment for the rail base. From this shoulder the body of the plate slopes 60 down to the outer web 6 thereof, which is tapered off at the ends as at 7, 8, and provided with a series of holes 9 at each end for use with a stop pin. The main portion of the base also tapers as at 7^a, 8^a, to meet the 65 tapers 7 and 8 at a point.

The clamps, of which a left side clamp only is shown, are made up with a base 10 and two hooked shaped ends 11 and 12. The base has a surface 13 on which rests the base 70 of the rail, and a cut-out portion 14 which passes under the tapered end of the tie plate. The hook 11 is shaped to engage firmly 75 over the base of the rail on the inside, and the hook 12 is shaped with a tapered side wall 15. The side wall of the cut-out portion is also tapered as at 16, so that the clamp can be hooked under a rail and driven over the pointed end of the tie plate to make a firm fit when driven home.

The outside spike hole, of which there need be but one, is formed in the shoulder portion as at 17.

As so constructed the tie plate will need be used ordinarily on every third or fourth 85 tie and is spiked down together with the rail and then the clamp driven into place and locked there by means of a cotter pin or other stop pin dropped in one of the holes 9.

The rail cannot creep with relation to the tie plate because it is firmly wedged against it by the clamp and the looseness of the spikes will not permit the rail to rise from the tie plate.

In relaying rails a crew can proceed by removing the inside spikes, knocking off the clamps, removing the old rail and resetting the new rail. A gang of two men can then follow along and replace and drive 100 up the clamps, thereby holding the new rails in perfectly safe condition temporarily, without driving a single spike. One of the tie plates with clamps at both ends will hold two rails together without permitting any 105 parting or creeping and without the use of any spikes.

In replacing ties, the spikes can be pulled and the tie slipped out without affecting the relation of the tie plate, clamp and rail, 110 since the clamp will hold the tie plate on the rail.

In general, my device makes for greater security of rails on ties against lifting, creeping, parting, turning out, or spreading.

Having thus described my invention, what I claim as new and desire to secure by Letters Patent, is:—

1. In a tie plate and clamp, the combination with a plate for mounting on a railroad tie to form a base against which a rail will rest, a tapered end to said plate extending lengthwise of a rail to be mounted on the plate, and a clamp adapted to engage said tapered end, and the base of a rail at a point removed from the said plate, for the purpose described.
2. In a tie plate and clamp, the combination with a plate for mounting on a railroad tie to form a base against which a rail will rest, a shoulder on the plate against which one side of the rail base will abut, and an independent clamp adapted for engaging the rail base at a point removed from the plate and also engaging the plate to hold the rail base up against said shoulder.
3. In a tie plate and clamp, the combination with a plate for mounting on a railroad tie to form a base against which a rail will rest, a shoulder on the plate against which one side of the rail base will abut, a tapered end to said plate, and a clamp adapted to be driven over said tapered end and to engage the rail.
4. A tie plate comprising a base for a rail

having a hole or holes therein for spikes, a shoulder for a rail base abutment, a hole or holes adjacent the shoulder for additional spikes, a tapered wing on one side of the plate, and a clamp having a portion to fit under and hook over the base of a rail lying on the plate, and a portion to fit under and hook over a wing on the plate, said last noted portion being shaped in tapered form to permit driving onto the said tapered wing.

5. A tie plate comprising a base for a rail having a hole or holes therein for spikes, a shoulder for a rail base abutment, a hole or holes adjacent the shoulder for additional spikes, a tapered wing on at least one side of the plate, and a clamp having a portion to fit under and hook over the base of a rail lying on the plate, and a portion to fit under and hook over a wing on the plate, said last noted portion being shaped in tapered form to permit driving onto the said tapered wing, and a stop pin for said clamp, said plate having a plurality of openings therein in which to place the stop pin.

6. In a tie plate and clamp, the combination of a tie plate having a rail abutment on the outer side thereof, and a clamp adapted to hook around the inner side of the base of a rail resting on the plate and around the outer side of the plate as well, for the purpose described.

GRANVILLE ADAMS.
